CLAIM

The ornamental design for an LED lens, as shown and described.

DESCRIPTION

FIG. 1 is a perspective view of an LED (light emitting diode) lens showing our new design.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof.

FIG. 7 is a bottom plan view thereof; and,

FIG. 8 is a cross-sectional view of the LED lens, taken from line 8-8 of FIG. 6.

1 Claim, 8 Drawing Sheets

FIG. 1

FIG. 2

FIG. 3

FIG. 4

FIG. 5
